UNITED STATES PATENT OFFICE.

JOHN S. PEOPLES, OF WASHINGTON, DISTRICT OF COLUMBIA.

AMMUNITION-RECEPTACLE.

1,343,374.

Specification of Letters Patent. Patented June 15, 1920.

Application filed August 6, 1918. Serial No. 248,644.

(FILED UNDER THE ACT OF MARCH 3, 1883, 22 STAT. L., 625.)

To all whom it may concern:

Be it known that I, JOHN S. PEOPLES, captain, ordnance, N. A., a citizen of the United States, stationed at Washington, D. C., at the Engineering Division, Office of the Chief of Ordnance, have invented an Improvement in Ammunition-Receptacles, of which the following is a specification.

The invention described herein may be used by the Government or any of its officers or employees in prosecution of work for the Government, or by any other person in the United States, without payment of any royalty thereon.

This invention generically relates to special receptacles for ammunition; more specifically it comprehends an improved safety device for transporting cartridges for machine gun use.

In the prevailing methods it has been customary to transport the cartridges in ordinary packing cases to the supply depot, where they are unpacked and placed in the belts by suitable cartridge filling machines.

These belts are then deposited in portable cases, and conveyed to machine guns. Not infrequently, as the belt is taken to its destination, the container is subjected to considerable jolting, due to the shock of bursting shells, and the uneven character of the terrain, which displaces the cartridges and results in jamming of the machine gun, when the belt with empty pockets is fed to the gun.

Obviously, exclusive of the annoyance, danger and delay incidental to the absence of one or more cartridges from the belt, the manifold stages through which the cartridges pass before attaining their ultimate destination, as well as the machines, operators and time required at each stage are objectionable.

One of the objects of this invention, therefore, is to overcome the preceding disadvantageous features, by providing a simple device, capable of positively maintaining the cartridges in their proper position in the belt; to eliminate the intermediate stages of filling and transferring the cartridges from one container to another by employing containers and belts, which after the initial loading at the manufacturing plant, are conveyed directly to the machine gun without being further disturbed. Han-

dling the cartridges in this manner conserves time, and permits the man power necessary to the operation of the filling machines at the ammunition base to be utilized for other purposes.

Another important phase of this invention is the locking device, securing the cartridges against accidental displacement, this device being constructed to enable quantity production at a comparatively nominal manufacturing cost.

Other points of this invention are the production of a container having dimensions, admitting of convenient handling for transportation purposes; means for securely binding the cartridges to prevent their becoming loose by virtue of jolts and the like, as well as to permit ready removal from the container when needed.

With these and other objects in view, my invention consists in certain novel details of construction, combination and arrangement of parts, to be more specifically set forth and claimed.

In the accompanying drawings in which corresponding parts are indicated by similar reference characters,

Figure 1 is a top plan view, the cover of the container being removed;

Fig. 2 is a fragmentary front elevation of the locking plate;

Fig. 3 is a similar rear elevation;

Fig. 4 is a fragmentary section on the line 4—4 of Fig. 2;

Fig. 5 is a top plan view, the cover of the container being removed, and illustrating a modified form of locking plate;

Fig. 6 is an illustration of the modified locking plate (as shown in Fig. 5) removed from the container;

Fig. 7 is a fragmentary perspective of the locking plate (illustrated in Figs. 5 and 6);

Fig. 8 is a front elevation of a further modified form, parts being broken away illustrating the construction of the locking plate and arrangement of belt and cartridges in the container;

Fig. 9 is a top plan view of the modified form shown in Fig. 8, a portion of the cover being broken away, illustrating the ribbed formation of the locking plate.

Briefly stated, this invention comprises a polygonal or circular container of metal or

other suitable material, a perforated plate fitting the cartridge necks and spacing elements off setting the plate so that it will bear against the edge of the belt and force the latter firmly on to the cartridge.

In the illustrated embodiment characterized by Figs. 1 to 4, inclusive, there is shown a rectangular container 1, preferably of metal, with dimensions sufficient to readily 10 house a cartridge belt 2, with its transversely extending cartridges 3.

Unless precautionary measures are taken, constant jarring of the container actuates the belt toward the necks of the cartridges.

15 For this reason, a rectangular, metallic follow plate 4, with perforations 5, is fitted within the container and interposed between the edge of the cartridge belt and one of its side walls with the cartridges projecting 20 through the perforations.

The lateral edges of follow plate 4 are turned inwardly, while its intermediate portion is transversely crimped at predetermined intervals, to form ribs 6, functioning 25 as spacing elements. The outer edge of ribs 6, abutting against the inner surface of the side wall of the container, forces the plate against the edge of the cartridge belt, and firmly presses the latter on to the cartridges. 30 As previously stated, spacing ribs 6 may be formed integral with the plate, as shown in Fig. 4 of the drawings, though any construction will suffice, provided plate 4 may be off-set to exert sufficient pressure 35 upon the edge of the cartridge belt to prevent its becoming disengaged from the cartridges. A binding strap 7 of any suitable material is bound around the cartridges 3, and sealed as at 8 to insure its securement.

40 Strap 7 materially assists in maintaining the belt and cartridges in compact formation.

To protect the base of the cartridges, a soft padding 9 of rubber or other yieldable 45 material is interposed between said base and the adjacent inner surface of the container. Padding 9 forces the cartridges, and incidentally the belt, outwardly and against the plate 4, coöperating with the previously 50 mentioned elements in producing a continuous pressure on the edge of the cartridge belt.

Although not shown, a suitable cover is to be positioned on the container, as will be 55 readily understood without further discussion.

In Figs. 5, 6 and 7 another form of spacing plate is utilized in lieu of that hereinbefore described. In this construction the 60 plate is reversed and the perforations are omitted; that is to say, follow plate 4 is positioned with its inner surface overlying the inner surface of the container, the spacing ribs 6 projecting outwardly so as to engage the edge of the belt. In this form,

the spacing ribs 6 are much closer together and more numerous to increase the number of pressure exerting surfaces in engagement with the belt.

Finger holes 10 are formed in certain of 70 the spacing ribs 6 to permit convenient removal of the plate when necessary (shown in Figs. 6 and 7 of the drawings). In other respects, this construction is similar to that previously described.

75 In the exemplification illustrated in Figs. 8 and 9 there is shown a circular container 11, embodying base 12, vertical wall 13 and cap 14. The cap 14 is provided with an offset flange 15, to embrace the outer edge of 80 the vertical wall 13, as clearly shown in Fig. 8. The dimensions of this container are sufficient to readily house the cartridge belt 2 and its cartridges 3. Cartridge belt 2 bound, in rolled formation by strap 7', is 85 deposited within the container, as shown in Fig. 8.

To meet the foregoing alterations, a circular plate 4', having perforations 5', is interposed within the container between the upper edge of the belt and the inner surface of the cap 14, the necks of the cartridges, as in the other constructions, projecting through the perforations of the plate, so that it may engage the edge of the belt. 90 Radially extending spacing ribs 6' offset the plate from the inner surface of the cap, effecting suitable pressure upon the edge of the belt to wedge the same firmly upon the cartridges.

95 Padding 9' of rubber or other similar yieldable material is likewise interposed between the inner surface of the container base 12, and the base of the cartridges, for the purpose of coöperating with the spacing plate 4' in securement of the cartridges. 105 In regard to strap 7' acting as a binder, it is to be noted that the free end of this strap is sealed, as at 8', for reasons hereinbefore stated.

110 In conclusion, it will be seen this invention provides a container of simple construction, which, after serving its purpose, may be discarded; affords effective means for positively maintaining the cartridges in their proper position in the belt, and insures a properly loaded belt being fed to the machine gun.

115 Having now described my invention, what I claim is:

120 1. In an ammunition receptacle, the combination with a container designed to accommodate a cartridge filled ammunition belt, of means within the container and contacting one of its walls for maintaining the belt and cartridges in relative position.

125 2. In an ammunition receptacle, the combination with a container designed to accommodate a cartridge filled ammunition belt; of means within the container and en-

gaging the cartridges for maintaining the belt and cartridges in relative operative position.

3. In an ammunition receptacle, the combination with a container designed to accommodate a cartridge - filled ammunition belt; of means coöperating with the belt, to hold the latter firmly upon the cartridges, substantially as described.
- 10 4. In an ammunition receptacle, the combination with a container designed to accommodate a cartridge filled ammunition belt; of means within the container, coöperating with one edge of the belt, to urge the latter firmly upon the cartridges substantially as described.
- 5 5. In an ammunition receptacle, the combination with a container designed to accommodate a cartridge filled ammunition belt; of means disposed within the container in offset relation with respect to one of its walls, and coöperating with one edge of the belt, to hold the latter firmly upon the cartridges, substantially as described.
- 20 6. In an ammunition receptacle, the combination with a container disposed to accommodate a cartridge filled ammunition belt; of a follow plate situated within and offset from one wall of the container, said plate coöperating with one edge of the belt to wedge the latter firmly upon the cartridges.
- 25 7. In an ammunition receptacle, the combination with a container disposed to accommodate a cartridge filled ammunition belt; of a perforated follow plate situated within the container, the necks of the car-

tridges projecting through the perforations therein, and means offsetting the plate from one wall of the container to force said plate 40 into engagement with an edge of the belt, substantially as described.

8. In an ammunition receptacle, the combination with a container disposed to accommodate a cartridge filled ammunition 45 belt; of a perforated plate situated within the container, the necks of the cartridges projecting through perforations therein; rearwardly extending spacing ribs offsetting the plate from one wall of the container to 50 hold said plate in coöperative relation with an edge of the belt, substantially as described.

9. In an ammunition receptacle, the combination with a container designed to fold- 55 ably accommodate a cartridge filled ammunition belt, and a binder to maintain the same in compact formation; of detachable means within the container effecting positive securement of the cartridges and their 60 belt; substantially as described.

10. In an ammunition receptacle the combination with a container designed to fold- 65 ably accommodate a cartridge filled belt, and a binder surrounding the cartridges to hold the same in compact formation; of a perforated plate situated within the container, the necks of the cartridges projecting through the perforations therein; spacing elements offsetting the plate from one 70 wall of the container to hold said plate in coöperative relation with an edge of the belt.

JOHN S. PEOPLES.
